UNITED STATES PATENT OFFICE

THEODORE W. HALLERBERG, OF BATTLE CREEK, MICHIGAN, ASSIGNOR TO LUBRICATION DEVICES INCORPORATED, OF BATTLE CREEK, MICHIGAN

PUMP FOR LUBRICATING SYSTEMS AND THE LIKE

Application filed May 13, 1929. Serial No. 362,541.

The main objects of this invention are:

First, to provide a pump for lubricating systems such as motor vehicles, machines having a plurality of bearings, or a plurality of machines, which is automatic in its operation and adapted to automatically stop when the pressure in the system has reached a predetermined point.

Second, to provide a pump embodying these advantages which is compact and capable of being mounted in a limited space.

Third, to provide a structure having these advantages which is comparatively simple and not likely to get out of repair.

Objects relating to details and economies of construction and operation of my invention will appear from the description to follow. The invention is defined and pointed out in the claims.

A structure which is a preferred embodiment of my invention is illustrated in the accompanying drawings, in which:

Fig. 1 is a fragmentary view mainly in vertical section of a structure embodying the features of my invention, the pump plunger being shown in its initial or retracted position, the control plunger being shown in its actuated position.

Fig. 2 is a fragmentary section on line 2—2 of Fig. 3 of certain parts shown in Fig. 1 with the pump plunger in actuated position and the control plunger in its initial position.

Fig. 3 is a fragmentary section on line 3—3 of Fig. 2.

Fig. 4 is a diagrammatic conventional view of the electro-magnet actuating means and the wiring therefor.

Referring to the drawings, the embodiment illustrated comprises a housing 1 having a vertical partition 2 therein providing a lubricant reservoir 3 and a housing chamber 4 for the operating mechanism.

The cylinder block designated generally by the numeral 5 has a bore 6 constituting a pump cylinder, the bore 7 constituting a control cylinder. The pump cylinder has a discharge 8 provided with a check valve 9. It also is provided with an inlet passage 10 opening to the side of the cylinder and com-

municating with the reservoir 3. This passage is provided with a check valve 11.

A relief passage 12 is formed in this cylinder block, this relief passage opening to the discharge 8 at the rear of the valve 9 and having a portion 13 opening transversely through the cylinder 6 and communicating with the reservoir.

The control cylinder is connected to the relief passage 12 by an inlet passage 14 controlled by the pressure actuated valve 15, the valve being held normally in closed position by means of the coiled spring 16.

The control cylinder is provided with an outwardly opening unloading valve 17 discharging to the relief passage 12.

The pump plunger 18 is adapted to constitute a valve for the relief passage, this passage being opened when the valve is in its fully retracted position, as shown in Fig. 1, so that the system may discharge back into the reservoir through the passage 12 and the control cylinder may discharge into this passage through its unloading valve 17.

The initial movement of the pump plunger closes this port and means are provided for limiting the return stroke of the plunger during its operation as a pump so that the relief passage is closed during such operation. This means, in the embodiment illustrated, comprises a control lever 19 which is pivoted at 20 and is connected by a link 21 to a slidable shouldered stop 22 disposed in alignment with the outer end of the plunger. When this stop is moved downward to bring its enlarged end into the path of the plunger, the stroke of the plunger is limited as described.

When the control lever is shifted to its initial position, as shown in Fig. 1, the stop is withdrawn, allowing the plunger to return to its relief passage opening position. A coiled spring 23 is provided for holding the lever in both its inoperative and operative positions. The plunger is provided with a return spring 24.

In the embodiment illustrated, the structure is actuated by an electromagnet, the armature 25 of which is mounted on the plunger, the coil 26 being suitably supported in operative relation thereto. A control rod

34' is provided for starting and stopping the apparatus. Control rod 34' is connected directly to the control lever 19, and the latter is connected to switch 33 by link 35 so that 5 when control rod 34' is actuated switch 33 is closed and when control lever 19 is actuated by control rod 34' or by plunger 31 to stop the apparatus switch 33 is opened.

A normally open starting switch or push 10 button 36 is provided in parallel circuit relation with switch 33. In starting the apparatus, switch 36 is first momentarily closed, causing the plunger rod to be moved, as described below, out of the path of the shoulder 15 dered part of block 22, permitting the latter to be moved by control rod 34 and lever 19 into the path of the plunger rod before its return stroke. Starting switch 36 is provided primarily for setting the apparatus in operation, inasmuch as when the control rod 34' is pulled to actuate the control lever 19 switch 33 is closed. In the meantime, starting switch 36, having performed its function, is released and returns to its normally open 20 position. The closing of the circuit through switch 33 or 36 energizes both the field and the core through the contact 28 which moves the core coil to the center of the field core, operating the plunger 18 and, at the same time, 25 pulling down the switch core 29 toward the field coil. This results because the core 29 is a laminated iron core and tends to move down toward the end of the field coil 26. The core 29 is carried by a spring 27.

30 During this downward movement, the contact 28 is maintained in operative relation until the core 29 strikes the top of the field core 26, when the contact 28 is broken deenergizing the field coil and the core coil. The spring 35 24 then returns the switch core until contact 28 is again made when the operation is repeated. This upward and downward stroke continues until the system is loaded, when 40 the switch 33 is opened through the actuation 45 of the plunger 31 in the cylinder 7.

The plunger 31 is provided with a rod portion 32 projecting into position to engage the control member 19 when the control plunger is actuated, thereby withdrawing the stop member 22 and allowing the plunger to return to its relief passage relieving position. The control member is operatively connected to the main switch 33 as described, so that this switch is opened and the pump stopped.

50 As soon as the pressure is relieved in the relief passage, the spring 34 will return the control plunger to its initial position, forcing the lubricant out of the control cylinder through its unloading valve. The plunger is 55 very rapidly operated and even with a relatively small electromagnet the lubricant may be discharged under very considerable pressure.

I have illustrated and described my improvements in an embodiment which I have

found highly satisfactory. I have not attempted to illustrate or describe certain embodiments and adaptations which I contemplate as it is believed that this disclosure will enable those skilled in the art to embody or adapt my improvements as may be desired. 70

Having thus described my invention, what I claim as new and desire to secure by Letters Patent, is:

1. In a pump, the combination with a reservoir, of a pump cylinder provided with an inlet connection to said reservoir and with a valved discharge, a pressure relief passage delivering to said reservoir and opening to said discharge passage at the rear of its said valve and to said pump cylinder at the front of its inlet, a control cylinder, an inlet connecting said relief passage to said control cylinder and provided with a pressure actuated valve, an unloading valve for said control cylinder delivering to said relief passage in advance of its opening to said pump cylinder, a pump plunger constituting a valve for said relief passage, a return spring for said pump plunger, an electro-magnet 90 for actuating said pump plunger, an automatically operating switch for said electro-magnet, a manually actuated control member, a stop operatively connected with said control member and adapted when in actuated position to limit the return stroke of said pump plunger and thereby close said relief passage, said relief passage being open when said pump plunger is in its fully retracted position, a pressure actuated control plunger arranged in said control cylinder and adapted when actuated to return said control member to inoperative position, and a return spring for said control plunger. 95

2. In a pump, the combination with a reservoir, of a pump cylinder provided with an inlet connection to said reservoir and with a valved discharge, a pressure relief passage delivering to said reservoir and opening to said discharge passage at the rear of its said valve and to said pump cylinder at the front of its inlet, a control cylinder, an inlet connecting said relief passage to said control cylinder and provided with a pressure actuated valve, an unloading valve for said control cylinder delivering to said relief passage in advance of its opening to said pump cylinder, a pump plunger constituting a valve for said relief passage, a return spring for said pump plunger, an electro-magnet for actuating said pump plunger, an automatically operating switch for said electro-magnet, a control means including a stop adapted when in actuated position to limit the return stroke of said pump plunger and thereby close said relief passage, said relief passage being open when said pump plunger is in its fully retracted position, a pressure actuated control plunger arranged in said control cylinder. 120

der and adapted when actuated to return said control means to inoperative position, and a return spring for said control plunger.

5 3. In a pump, the combination with a reservoir, of a pump cylinder provided with an inlet connection to said reservoir and with a valved discharge, a pressure relief passage delivering to said reservoir and opening 10 to said discharge passage at the rear of its said valve and to said pump cylinder at the front of its inlet, a control cylinder, an inlet connecting said relief passage to said control cylinder and provided with a pressure actuated valve, an unloading valve for said control cylinder delivering to said relief passage in advance of its opening to said pump cylinder, a pump plunger constituting a valve for said relief passage, means for 15 actuating said pump plunger, a manually actuated control member, a stop operatively connected with said control member and adapted when in actuated position to limit the return stroke of said pump plunger and 20 thereby close said relief passage, said relief passage being open when said pump plunger is in its fully retracted position, and a pressure actuated control plunger arranged in said control cylinder and adapted when actuated to return said control member to inoperative position.

4. In a pump, the combination with a reservoir, of a pump cylinder provided with an inlet connection to said reservoir and 25 with a valved discharge, a pressure relief passage delivering to said reservoir and opening to said discharge passage at the rear of its said valve and to said pump cylinder at the front of its inlet, a control cylinder, an inlet connecting said relief passage to said control cylinder and provided with a pressure actuated valve, an unloading valve for said control cylinder delivering to said relief passage in advance of its opening to 30 said pump cylinder, a pump plunger constituting a valve for said relief passage, means for actuating said pump plunger, a control means including a stop adapted when in actuated position to limit the return stroke of 35 said pump plunger and thereby close said relief passage, said relief passage being open when said pump plunger is in its fully retracted position, and a pressure actuated control plunger arranged in said control cylinder and adapted when actuated to return said control means to inoperative position.

5. In a pump, the combination of a pump cylinder provided with an inlet and with a valve discharge, a pressure relief passage 40 opening to said discharge at the rear of its valve and to said cylinder at the front of its inlet, a pump plunger constituting a valve for said relief passage, a return spring for said pump plunger, an electro-magnet for actuating said pump plunger, a switch for

said electro-magnet actuated by the movement of the pump plunger, a control means including a stop adapted when in actuated position to limit the return stroke of said pump plunger and thereby close said relief passage, said relief passage being open when said pump plunger is in its fully retracted position, and a pressure actuating means operatively connected to the discharge of the pump for returning said stop to its initial position and thereby permit the plunger to move to relief passage opening position. 70

6. In a pump, the combination of a pump cylinder provided with an inlet and with a valved discharge, a pressure relief passage opening to said discharge at the rear of its valve and to said cylinder at the front of its inlet, a pump plunger constituting a valve for said relief passage, means for actuating said pump plunger, a control means including a stop adapted when in actuated position to limit the return of said pump plunger and thereby close said relief passage, said relief passage being open when said pump plunger is in its fully retracted position, and a pressure actuating means operatively connected to the discharge of the pump for returning said stop to its initial position and thereby permit the plunger to move to relief passage opening position. 75

7. In a pump, the combination of a pump cylinder provided with an inlet and with a valved discharge, a pressure relief passage opening to said discharge at the rear of said valve and to said cylinder at the front of its inlet, a pump plunger constituting a valve for said relief passage, a return spring for said pump plunger, an electro-magnet for actuating said pump plunger, a switch for said electro-magnet actuated by the movement of the pump plunger, and a control means including a stop adapted when in actuated position to limit the return stroke of said pump plunger and thereby close said relief passage, said relief passage being open when said pump plunger is in its fully retracted position. 80

8. In a pump, the combination of a pump cylinder provided with a valved inlet and with a valved discharge, a valve associated with said discharge, a pressure relief passage opening to said discharge at the rear of said valve and to said cylinder at the front of its inlet, a pump plunger constituting a valve for said relief passage, a return spring for said pump plunger, means for limiting the return stroke of the pump plunger thereby maintaining the same in relief passage closing position, pressure actuated means operatively associated with said stroke limiting means, an electro-magnet for actuating said pump plunger, and a switch for said electro-magnet actuated by the movement of the pump plunger. 105

9. In a pump, the combination of a cylin- 110

der provided with an inlet and with a valved discharge, a pressure relief passage opening to said discharge passage at the rear of its said valve and to said pump cylinder at the front of its inlet, a pump plunger constituting a valve for said relief passage, a return spring for said pump plunger, an electro-magnet for actuating said pump plunger, an automatically operating switch for said electro-magnet, and a stop member adapted when in actuated position to limit the return stroke of said pump plunger thereby maintaining the same in relief passage closing position, said relief passage being opened when the pump plunger is in its fully retracted position.

10. In a pump, the combination of a cylinder provided with an inlet and with a valved discharge, a pressure relief passage opening to said discharge passage at the rear of its said valve and to said pump cylinder at the front of its inlet, a pump plunger constituting a valve for said relief passage, a return spring for said pump plunger, means for limiting the return stroke of the pump plunger thereby maintaining the same in relief passage closing position, pressure actuated means operatively associated with said stroke limiting means, an electro-magnet for actuating said pump plunger, and an automatically operating switch for said electro-magnet.

11. In a pump, the combination of a pump cylinder provided with inlet and discharge and with a relief means connected to said discharge, a pressure actuated element connected to said relief means, a pump plunger operatively associated with said relief means, a stop member operatively associated with said pump plunger and adapted when in actuated position to limit the return stroke of said pump plunger thereby maintaining it in relief closing position, and operating connections from said pressure actuated element to said stop, said pressure actuating element being provided with an unloading valve discharging through said relief means.

12. In a pump, the combination of a pump cylinder provided with inlet and discharge and with a relief means connected to said discharge, a pressure actuated element connected to said relief means, a pump plunger operatively associated with said relief means, a stop member operatively associated with said pump plunger and adapted when in actuated position to limit the return stroke of said pump plunger thereby maintaining it in relief closing position, and operating connections from said pressure actuated element to said stop.

13. In a pump, the combination of a pump cylinder and coacting plunger, said cylinder being provided with an inlet and discharge and with a relief passage connected to said discharge and controlled by the pump plunger,

er, and a control means for said pump plunger including a pressure controlled element operatively connected to the discharge, said pressure controlled element being also provided with an unloading valve controlled by said pump plunger.

14. In a pump, the combination of a pump cylinder and coacting plunger, said cylinder being provided with an inlet and discharge and with a relief passage connected to said discharge and controlled by the pump plunger, and a control means for said pump plunger including a pressure controlled element operatively connected to the discharge.

In witness whereof I have hereunto set my hand.

THEODORE W. HALLERBERG.
